DISTILLATION OF TAR

Application filed September 11, 1928. Serial No. 305,265.

This invention relates to improvements in the distillation of tar and the production therefrom of distillate oils and pitch residues, and it includes improvements both in method and apparatus. The improved method and apparatus of the present invention enable increased yields of distillate oils to be obtained as compared with present methods of distillation in externally heated stills, and 10 enable high melting point pitches to be directly produced as a result of the distillation.

The present process of tar distillation is a continuous process in which the tar is first subjected to distillation in a pipe coil still in 15 which it is pumped through a pipe coil under pressure and heated therein to a high temperature and in which the pipe coil discharges into a vapor box or chamber where the oil vapors are separated from the pitch residue and from which the oil vapors are 20 withdrawn to a condenser; and in which the pitch residue from the pipe coil still is passed continuously to a vacuum box or still where it undergoes further distillation with its self- 25 contained heat and where an additional amount of heavy oil is distilled therefrom and a pitch of higher melting point produced. The pipe coil still may be a single stage or multi-stage still. The vacuum box 30 or still need not be independently heated, although additional heating may be employed. The present process makes use of the large amount of sensible heat contained in the pitch discharged from the vapor box of the pipe 35 coil still to distill an additional amount of heavy oil from the pitch by reducing the pressure on this pitch after it has been produced in the pipe coil still, and after it has been separately withdrawn from such still. 40 The improved apparatus of the present invention includes a pipe coil still, which may be a single stage or multi-stage pipe coil still, in which the tar is heated in a pipe coil under pressure and discharged therefrom into a 45 vapor box or separating chamber where the vapors are separated from the pitch residue, together with a vacuum box or still arranged to draw the hot pitch from the pipe coil still into the vacuum still and to effect further 50 distillation of oils from the pitch by reduc-

tion in pressure while it is still at a sufficiently high temperature to enable such distillation on reduction of pressure to take place. The apparatus includes pressure and vacuum regulating means whereby the pipe 55 coil still can be operated with pressure on the tar passing through the pipe coil, but with a vapor box at atmospheric pressure or approximately atmospheric pressure, and with the vacuum box or still under a high vacuum approaching the maximum vacuum obtainable. The apparatus includes suitable condensing 60 means for condensing the distillate oils fractionally to recover different oil fractions therefrom. It also includes suitable means 65 for preheating the tar.

In the operation of pipe coil stills for the distillation of tar, the pitch produced as a result of the distillation is usually drawn off at a high temperature as a finished product 70 and is permitted to cool and solidify, or is passed to other stills in which it can be subjected to further distillation for the production of additional oil therefrom. In the pipe 75 stills themselves, there is a limit to the extent to which the distillation can be carried because, if the tar is heated to too high temperatures, it undergoes objectionable decomposition, with decrease in oil yields and increase in pitch production. If the tar is kept at a 80 sufficiently low temperature to avoid excessive decomposition of the pitch and tar, the oil yields are limited and the melting point of the pitch is limited.

The present invention enables increased oil 85 yields to be obtained, and a pitch of higher melting point to be directly produced, in a continuous manner, without the supply of any additional heat other than that supplied in the tar heater or pipe coil still. It enables 90 the pipe coil still to be operated at a temperature such that objectionable decomposition is avoided or minimized, and it supplements the pipe coil still distillation with a vacuum distillation which makes use of the heat contained in the high temperature pitch escaping 95 from the pipe coil still. This further distillation is accomplished without heating the pitch to a higher temperature and, where additional heat is not supplied to the pitch, the distilla- 100

tion is accomplished with lowering in temperature of the pitch, so that the higher melting point pitch withdrawn from the vacuum still will be at a lower temperature than that withdrawn from the pipe coil still.

It will be seen that, in the present process, the vacuum is not applied to the vapor box of the pipe coil still, but is only applied to the hot pitch residue produced by the pipe coil still after this pitch residue has been withdrawn from the vapor box of such still. It is important that the high vacuum should not be applied directly to the vapor box of the pipe coil still because the large amount of oil vapors separated in this vapor box would be expanded by the vacuum and their condensation would be made more difficult, particularly the condensation of the lighter vapors of lower boiling point oils. In the present process, these vapors are taken off from the vapor box of the pipe coil still at atmospheric pressure, or at a pressure approximating atmospheric, and only the pitch residue is passed to the vacuum box and subjected to the high vacuum. This pitch residue will have been freed from a large part of the normal oil content of the tar distilled, and particularly of the lower boiling oils, so that the pitch residue will contain only or for the most part higher boiling oils. When these oils are distilled in the vacuum box or still, they can be readily condensed even though a high vacuum is maintained, because of their high boiling point. A high vacuum can also be much more readily maintained where only the hot pitch residue is subjected to the vacuum, than where the vacuum is applied directly to the entire vapor production of the pipe coil still in the vapor box of that still.

Pitches of high melting point can be produced by the present process, for example, pitches of melting points up to around 400° F or higher. Such high melting point pitches can, moreover, be produced at the same time that high oil yields are obtained from the tar distilled. The pitches are, moreover, distinguished from pitches of similar melting points produced by present day methods from externally heated stills by having in general a lower so-called free carbon content. The oils produced by the present process include not only the lower and medium boiling point oils, but also the high boiling point oils obtained during the high vacuum distillation and some of which heavy or high boiling point oils may be, or may contain constituents of, a semi-solid or solid consistency. In order to avoid solidification of the high melting point pitch or of the heaviest of the oil constituents, it is important to provide suitable insulation for the parts of the apparatus through which the oils and pitch are passed so as to permit withdrawal thereof from the apparatus in a liquid and thinly fluid state.

The present process enables a wide range

of oil fractions to be produced, and enables the different fractions to be regulated to obtain oil fractions suitable for various purposes, such as carbolic oils, creosote oils, etc.

The temperature to which the tar or pitch is heated in the pipe coil still can be somewhat varied, but in general the temperature should not be sufficiently high to cause objectionable decomposition of the tar or pitch passing through the still. The pitch leaving the pipe coil still may be, for example, at a temperature around 800° F. and the pitch may itself have a melting point of around 240° F., more or less. In the vacuum box or still the vacuum maintained may be around 27 to 29.7 inches of mercury. Under such high vacuum, a considerable part of the oil content of the hot pitch will be distilled which would not be distilled at the same temperature under atmospheric pressure.

The distillation of tar in a pipe coil still has the advantage that the tar can be rapidly and continuously pumped through the pipe coil and heated therein to a high temperature without maintaining the tar at a high temperature for more than a very short period of time. When the tar is heated to the high temperature, it is immediately discharged from the pipe coil into the vapor chamber of the still where the vapors which are produced at such temperature are drawn off and condensed. The vaporization which takes place in the vapor chamber of the still may result in lowering the temperature of the pitch somewhat from that to which the tar is heated in the pipe coils, but the pitch will still be at a sufficiently high temperature so that, when "flashed" by the sudden reduction of pressure, a considerable further distillation will take place. The maximum temperature to which the tar or pitch is heated, is that in the pipe coils, and, by regulating and limiting this temperature, and the period of time to which the tar or pitch is subjected to it, objectionable decomposition of oil constituents can be largely avoided, thus giving a pitch of lower so-called free carbon content, and an increased oil yield.

The invention will be further described in connection with the accompanying drawings, which are of a conventional or diagrammatic character, and in the nature of flow sheets, and which show arrangements of apparatus embodying the invention and adapted for the practice of the process of the invention; but it will be understood that the invention is not limited thereto.

In the accompanying drawings, Figs. 1 and 2 are diagrammatic arrangements or flow sheets showing two somewhat different modifications of apparatus. The drawing is not intended to be made to scale.

The apparatus of Fig. 1 includes a single stage pipe coil still 1, heated by suitable furnace 2. Tar to be distilled is supplied

through the supply pipe 3 by means of pump 4 from a suitable supply of tar (not shown). From the pipe coil, the heated tar passes through the pipe 5 to the vapor box 6. The tar will be forced through the pipe coil rapidly and under pressure and will discharge into the vapor box which is at atmospheric pressure, or approximately so, and where oil vapors will separate from the unvaporized pitch. The vapors pass through pipe 7 to condenser 8, which may be of any suitable construction, and the oil outlets from which are not shown.

The pitch collecting in the vapor box 6 passes through the pipe 9 having pressure reducing valve 11 therein to the vacuum box 10 which is maintained under a high vacuum, for example, a vacuum corresponding to 29.7 inches of mercury. The vacuum box or still 10 is arranged some distance above the vapor box 6 and the vacuum is relied upon to draw the pitch from the vapor box to the vacuum box. Immediately upon reduction of pressure at the pressure reducing valve 11, distillation of some of the oils contained in the pitch will take place and the resulting oil vapors will assist in forcing the pitch into the vacuum box. The vacuum box cannot be located too far above the vapor box 30 because the vacuum is relied upon to draw the pitch from the vapor box to the vacuum box. In order that a high vacuum may be maintained and the flow of pitch from the vapor box to the vacuum box controlled, it is 35 important to provide a pressure reducing valve 11 in the line 9 leading from the vapor box 6 to the vacuum box 10.

The vapors distilled from the pitch in the vacuum box pass through the vapor line 12 to the condenser 13, thence through the line 18 to a second condenser 19. The oil condensed in the condenser 13 flows through the pipe 14 to a seal tank 15 from which it may be drawn off, for example, through measuring pan 16 to an oil receiver 17. The oil condensed in the condenser 19 similarly flows through the pipes 20 and 21 to the oil receiver 22. The pitch residue from the vacuum box or still 10 flows through the pitch line 26 to the seal tank 27 and thence to a suitable place of pitch storage 28. The lines 14, 20—21, and 26 are sufficiently long, and the vacuum box and condensers are arranged sufficiently above the oil and pitch seals or receptacles, 55 that barometric columns of oil or pitch will be maintained in these lines so that the oil and pitch will flow out continuously by gravity against the high vacuum maintained in the vacuum still. Between the second condenser 19 and the vacuum pump 25 is arranged an oil and air separator 23 from which any separated oil flows through the pipe 24 to the pipe 21 and then to the receiver 22. Any suitable type of vacuum pump or vacuum producing means can be employed, a

three stage ejector type of vacuum pump being suitable and preferable.

According to a preferred method of operation, tar which is to be distilled is used for cooling in the condensers, the tar being thereby preheated. Various arrangements for circulating the tar through the condensers may be employed, that shown in the drawings combining countercurrent and parallel flow features to advantage. The tar supplied to the line 29 by the pump 30 is divided, that portion which is used to cool the vapors in the condenser 19 being returned through the line 31 and united with the balance of the tar from the line 29 before entering the condenser 8. The combined tars are employed to cool the vapors at the exit of the condenser 8, then all or a part of the tar is conveyed through pipe 32 to the condenser 13 where it is used for condensing the vapors passing through this condenser. The tar is then returned to the condenser 8 and brought into indirect contact with the vapors entering this condenser. The tar which has thus been gradually heated by indirect contact with the hot vapors in the various condensers may be sent to the continuous pipe still alone or blended with tar from another source.

In the drawings, insulation is not shown but it will be understood that in practice the line conveying the hot pitch to and from the vacuum box as well as the vacuum box itself and other parts of the apparatus will be suitably insulated to avoid heat losses and in particular to avoid cooling of the pitch unnecessarily before it is discharged from the apparatus. With pitch of high melting point, around 400° F., it is important to withdraw the pitch while it is still hot and thinly fluid. Such pitch can then be run to storage tanks or receptacles and be permitted to solidify, or it can be continuously solidified by means of special cooling treatment or devices (not shown).

The flow sheet of Fig. 2 shows a somewhat modified apparatus in which a two-stage pipe coil still is shown with provision for fractional condensation of the oils distilled in such stills and also in the vacuum still.

In Fig. 2 the first pipe coil still 35 is supplied with tar through the supply pipe 36 by means of a pump 37 from one or the other of the crude tar storage tanks 38 and 39. From this pipe coil, the heated tar passes through the pipe 40 to the vapor box 41 from which the pitch flows through the pipe 42 to the storage tank 43. This pitch is drawn off through the pipes 44 and 45 and pumped by the pump 46 to the second pipe coil still 47 which discharges through the pipe 48 to the second vapor box 49. The pitch residue from this second vapor box passes through the pipe 50 and past the pressure reducing valve 51 to the vacuum box or still 52. The pitch residue from this vacuum box flows through the line

53 to the seal box 54 and thence through line 55 to the pitch receiver 56.

The vapors separated in the first vapor box 41 flow through line 57 to the first condenser 58 which is shown as a multi-stage condenser. 5 The uncondensed vapors then pass through pipe 59 to the second condenser 60 from which the still uncondensed vapors pass through line 61 to another condenser 62 and finally 10 line 63 to a final worm condenser 64. The condensates from this last condenser flow through line 65 to an oil receiver 66.

The condensers 58, 60, 62 and 64 provide for fractional condensation of oils from the vapors and the separate collection of different oil fractions. The condensers 58 and 60 are shown as multi-stage condensers with separate oil outlet pipes 67 from the different stages and with pipe connections 68 leading to one or another of three storage tanks 20 69 for the oil fractions.

The vapors separated in the vapor box 49 pass through vapor line 70 to the first condenser 71, from which the uncondensed vapors pass through line 72 to the second condenser 73, thence through line 74 to a third condenser 75 and finally through line 76 to a final worm condenser 77. The condensate from this final condenser flows through line 30 78 to the oil receiver 66. The condensers 71 and 73 are shown as fractional condensers. The oil fractions from different sections of these condensers and from the condenser 75 are drawn off through pipes 79 and 80 to one 35 or another of the oil receivers 81. By regulating the valves in the pipes 79 and 80, the different oil fractions can be drawn off separately and kept separate. A diagrammatic arrangement of condensers is understood to 40 be illustrated, since it will be evident that a larger or smaller number of oil fractions can be obtained depending upon the number and operation of the fractional condensers applied.

45 The vapors separated in the vacuum chamber 52 pass through line 91 to the first condenser 92 from which the uncondensed vapors pass through line 93 to a second condenser 94. This second condenser connects 50 through line 96 to a three stage vacuum pump shown as a three stage steam ejector pump 97. The condensate from the condensers 92 and 94 may be drawn off through the lines 98 and 99. The line 98 passes 55 through the seal tank 100 to the oil receiver 101 and the line 99 passes through the seal tank 102 to the oil receiver 103.

The final condenser 94 is shown as a water cooled condenser, having water connecting 60 pipes 95. The other condensers, except the worm condensers 64 and 77, are shown as cooled by the tar which is thereby preheated, with resulting heat economy. The condensers 64 and 77 are worm condensers, cooled by 65 water.

The tar for cooling the condensers is supplied through line 82 by means of pump 83 and passes first through the condenser 62 where it is brought into indirect heat exchanging relation with the vapors passing 70 through this condenser. The tar then passes successively to the condensers 60, 58, 92, 75, 73 and 71, being finally discharged through the line 90 into the vapor box 41. In each of these condensers the tar passes in indirect 75 contact with the oil vapors but in heat interchanging relation thereto. The action of this tar is to cool the vapors and to condense the oils therefrom, while the tar is itself progressively heated to a high temperature. The 80 flow is countercurrent, the cold tar passing first to the condensers where the lighter oils are to be condensed and passing finally through the condensers where the vapors are at the highest temperature. The tar 85 circulating pipes between the various condensers are indicated respectively at 84, 85, 86, 87, 88, 89 and 90. The tar is preheated to such a temperature that when it enters the vapor box 41 more or less of its oil content 90 will be vaporized, particularly where the tar is maintained under pressure while it is forced through the condensers, and the pressure is released when it enters the vapor box. The residue remaining after the separation 95 of vapors in the vapor box joins with the pitch residue from the first pipe coil still and together these go to the second pipe coil still.

The pitch and oil lines 53, 86, 98 and 99 of Fig. 2 are sufficiently long, and the vacuum 100 box and its condensers are located a sufficient distance above the oil receivers or seal boxes or tanks that barometric columns of pitch and oil will be maintained in these pipes, thereby insuring maintenance of the vacuum in the 105 vacuum box, and continuous flow of gravity of the oil and pitch from the vacuum apparatus.

In the drawings, no separate heating provision is shown for heating the pitch in the 110 vacuum box. The heat content of the pitch is such that a considerable distillation of oil will take place on reduction of pressure from atmospheric to a high vacuum, even where no added heat is supplied. In such case, the further distillation by flashing under vacuum is 115 obtained entirely by the self-contained sensible heat of the hot pitch residue from the pipe coil stills, and this heat is made available by the reduction in pressure from atmospheric 120 to the high vacuum. In order to obtain maximum distillation, where additional heat is not employed, it is important to avoid unnecessary loss of heat by radiation, by providing heavy insulation, etc. When additional heat is supplied to the pitch going to or passing through the vapor box, an additional amount of oil can be distilled and a higher melting point pitch produced.

It will thus be seen that the present invention 130

tion provides an improved method and apparatus for distilling tar in a continuous manner and with notable heat economy, as well as with the production of a high melting point pitch and a high oil yield. It will further be seen that the distillation is accomplished without objectionable heating of the tar or pitch to a high temperature, and that the maximum temperature to which the tar or pitch is heated in the pipe coil still, is not exceeded in the further distillation of the pitch residue, but that this further distillation can be accomplished with lowering of temperature and reduction or avoidance of further objectionable decomposition.

We claim:

1. The method of distilling tar and of producing distillate oils and high melting point pitch therefrom, which comprises heating the tar while flowing in a restricted stream of narrow cross-section in a continuous manner without objectionable decomposition, discharging the heated tar into an expansion zone with sudden volatilization of a large part of the normal oil content of the tar, cooling the vapors to condense distillate oils, withdrawing the pitch residue and subjecting it to a high vacuum while it is still at a temperature sufficiently high to effect distillation of additional oils therefrom.

2. The method of distilling tar and of producing distillate oils and pitch therefrom, which comprises forcing the tar continuously under pressure through a pipe coil and heating it therein to a temperature sufficient to vaporize considerable proportions of the oil contained in the tar, discharging the resulting product into a vapor separating zone at approximately atmospheric pressure and thereby effecting separation of oil vapors from pitch residues, drawing off the oil vapors and subjecting them to condensation to recover distillate oils therefrom, drawing off the hot pitch residue and subjecting it to a high vacuum while it is still at a high temperature and thereby effecting further distillation of oils therefrom with reduction of temperature, condensing the distillates produced by such vacuum distillation, and separately drawing off the pitch residue from such vacuum distillation.

3. The method of distilling tar and of producing distillate oils and pitch residues therefrom, which comprises heating the tar flowing in a restricted stream of narrow cross-section in a continuous manner without objectionable decomposition, discharging the heated tar into an expansion zone, separating oil vapors from the resulting pitch residue in the expansion zone, cooling the vapors to produce distillate oils, drawing off the pitch residue through a pressure reducing and regulating valve to a vacuum box or still while it is still at a high temperature and thereby effecting further distillation of oils from the

pitch, the flow of pitch from the pipe coil still to the vacuum still being accomplished by the vacuum maintained in the vacuum still and being regulated by the pressure regulating valve.

4. The method of distilling tar and of producing distillate oils and pitch residues therefrom, which comprises first repeatedly heating the tar flowing in a series of restricted streams of narrow cross-section in a continuous manner without objectionable decomposition, drawing off vapors resulting from each heating of the tar and condensing distillate oils therefrom, drawing off the hot pitch residue from such distillation and subjecting it while it is still at a high temperature to a high vacuum to effect further distillation thereof and separately drawing off the vapors produced from such distillation and condensing them while still under a high vacuum.

5. The method of distilling tar and of producing distillate oils and pitch residues therefrom, which comprises continuously heating the tar flowing in a restricted stream of narrow cross-section to approximately the maximum temperature to which it can be heated without objectionable decomposition, discharging the heated tar into an expansion zone, withdrawing the vapors produced by such distillation and condensing the oils therefrom, withdrawing the pitch residue from such distillation and subjecting it to a high vacuum while it is still at a high temperature and thereby effecting further distillation of oils therefrom without objectionable decomposition of the pitch, and separately condensing the distillates so produced.

6. The method of distilling tar and of producing distillate oils and pitch residues therefrom, which comprises first subjecting tar to distillation at substantially atmospheric pressure to produce distillate oils and a pitch residue, withdrawing the pitch residue continuously while it is still at approximately the temperature of the first distillation and immediately subjecting it to a high vacuum to effect further distillation of high boiling point oils therefrom by the self-contained heat of the hot pitch.

7. The method of distilling tar and of producing distillate oils and pitch residues therefrom in a continuous manner, which comprises supplying the tar to be distilled to a still, heating the tar therein thereby distilling oils therefrom and producing a pitch residue, withdrawing the pitch residue continuously while it is still at practically its maximum temperature and immediately subjecting it to a high vacuum to effect distillation of additional oils therefrom by the self-contained heat of the pitch under the high vacuum.

8. An apparatus for distilling tar, comprising a pipe coil still having a heating coil

and a vapor separating chamber with means for separately withdrawing the vapors, a vacuum chamber, means connecting the vapor separating chamber with the vacuum chamber to permit flow of pitch therethrough, pressure reducing and regulating means in such connection, and means for maintaining a high vacuum in such vacuum chamber, the arrangement being such that the hot pitch from the pipe coil still can be immediately and directly conveyed while at practically its maximum temperature to the vacuum chamber, whereby the heat contained in the hot pitch can be employed for distillation in the hot pitch can be employed for distillation of additional amounts of oil therefrom.

9. An apparatus for distilling tar, comprising a pipe coil still having at least one pipe coil and vapor separating chamber, a pitch discharge for the pitch produced by such distillation, a vacuum chamber, means for maintaining a high vacuum therein, means connecting a vapor chamber of the pipe coil still with the vacuum chamber having a pressure reducing and regulating device therein, said apparatus being so arranged that the pitch residue from the pipe coil still will be drawn continuously by means of the vacuum through the pressure regulating device into the vacuum chamber for further distillation.

10. The method of distilling tar and of producing distillate oils and high melting point pitch therefrom, which comprises heating the tar while flowing in a restricted stream of narrow cross-section in a continuous manner, discharging the heated tar into an expansion chamber with resulting production of distillate oils and a pitch residue, withdrawing the pitch residue and subjecting it to a vacuum of at least twenty-seven inches to effect distillation of additional oils and the production of a high melting point pitch.

11. The method of distilling tar and of producing distillate oils and pitch residues therefrom in a continuous manner, which comprise supplying the tar to be distilled to a still and heating the tar therein and distilling oils therefrom and producing a pitch residue, withdrawing the pitch residue continuously while it is still at practically its maximum temperature and subjecting it to a vacuum of at least twenty-seven inches to effect distillation of additional oils therefrom by the self-contained heat of the pitch under a high vacuum.

12. The method of distilling tar and of producing distillate oils and pitch residues therefrom, which comprises first subjecting tar to distillation at substantially atmospheric pressure to produce distillate oils and a pitch residue, withdrawing the pitch residue, withdrawing the pitch residue during

distillation while it is still at approximately the temperature of the first distillation and without substantial heat loss subjecting it to a vacuum to effect further distillation of high boiling point oils therefrom by the self-contained heat of the hot pitch. 70

13. An apparatus for distilling tar, comprising a continuous tar still including a vapor box having means for supplying tar thereto continuously and for removing oil vapors therefrom, a vacuum chamber with means for maintaining a high vacuum therein, a connection between the vapor box and the vacuum chamber for conveying the pitch residue from the vapor box to the vacuum chamber together with means for regulating the reduction of pressure on the pitch, the arrangement being such that the hot pitch from the vapor box can be immediately and directly conveyed while at practically its maximum temperature to the vacuum chamber, whereby the heat contained in the hot pitch can be employed for distillation of additional amounts of oil therefrom. 80 85

14. The method of distilling tar and of producing distillate oils and pitch residues therefrom, which comprises first subjecting tar to distillation at substantially atmospheric pressure to produce distillate oils and a pitch residue, withdrawing the pitch residue during distillation while it is still at approximately the temperature of the first distillation and without substantial heat loss subjecting it to a high vacuum to effect further distillation of high boiling point oils therefrom by the self-contained heat of the hot pitch. 90 95 100

15. The method of distilling tar and of producing distillate oils and pitch residues therefrom in a continuous manner, which comprises supplying the tar to be distilled to a still and heating the tar therein and distilling oils therefrom and producing a pitch residue, withdrawing the pitch residue during distillation while it is still at practically its maximum temperature and immediately subjecting it to a high vacuum to effect distillation of additional oils therefrom by the self-contained heat of the pitch under the high vacuum. 105 110 115
